UNITED STATES PATENT OFFICE

2,420,787

EXTENSION TABLE

Thurlow E. McFall, Sparta, Mich., assignor to
 Michigan Arcraft Company, Sparta, Mich., a
 corporation of Michigan

Application May 4, 1942, Serial No. 441,636

2 Claims. (Cl. 311—42)

1

This invention relates to a drop leaf extension table. Primarily the invention is directed to an extension table of the character mentioned in which the permanent horizontal top member of the table is solid or undivided.

In general heretofore, drop leaf extension tables have such permanent top member divided into two parts which are moved away from each other when the table is opened for extension and for the reception of fillers in the open space between the two parts of the permanent table top. When the table is at its smallest size, not extended, there is a separation apparent between the two parts of the table top which is not only unsightly, the whole table top not presenting a smooth and unbroken surface, but particularly at the division may have a slight projection of one part of the top above the other either wholly or partly and at either one or both sides of the division separation.

A further object of the invention is to provide a drop leaf extension table which when not in use will occupy relatively small space. Also by raising the drop leaves to horizontal position a table having an effective top in sufficient area for many purposes will be produced; yet the area of the table may be greatly increased by extension and supplying of filler leaves to increase the supporting area of the table. The construction is also practical and economical to produce and may be manufactured commercially at low cost. Moreover, the table which I have devised is strong and durable and has a life equal, it is believed superior, to that of other tables of drop leaf extension character.

An understanding of the invention may be had from the following description taken in connection with the accompanying drawings, in which,

Fig. 1 is an end elevation of a table embodying my invention showing the table in its least space occupying condition.

Fig. 2 is a plan view of the table with an initiation of extension of such table at one side.

Fig. 3 is a fragmentary vertical section through the table extended to one side for a distance and the space filled with suitable filler leaves.

Fig. 4 is a fragmentary enlarged transverse section illustrating the special form of filler leaves used with and forming a part of my invention.

Fig. 5 is a plan view of the table extended in both directions away from the central single piece permanent top.

Fig. 6 is a side elevation of the table shown in Fig. 5 as it appears in use after extension and addition of filler leaves.

2

Fig. 7 is a plan view of a different structural form or embodiment of my invention, and

Fig. 8 is a longitudinal vertical section through the upper portion thereof with filler leaves in place.

Like reference characters refer to like parts throughout the different figures of the drawings.

The permanent horizontal top of the table indicated at 1 is of rectangular form. At its longer edges drop leaves 2 and 3 are hingedly mounted by means of hinges 4 and have association with such longer edges of the top member 1 whereby when the drop leaves are raised to horizontal position a smooth table surface will be provided.

15 At each of the longer edges of the top member 1 it is grooved to form a groove 5 of the shape shown in Fig. 3, and the adjacent edges of the drop leaves 2 and 3 are correspondingly shaped as ribs indicated at 6 to fit and fill the grooves 20 when raised to operative position. In order to provide for proper cooperation between the grooved edges 5 of the top member 1 and the ribbed edges 6 of the drop leaves 2 and 3, the hinges 4 are connected to the upper edges of 25 cross rails 15 and to the drop leaves at their inner faces. The hinges are spaced from the upper horizontal edge of each leaf, when the latter is in lowered position, a distance substantially equal to the greatest vertical dimension of the groove 30 formed at the longer edge of the table top 1.

A central pedestal 7 is secured at its upper end to the under side of the top member 1 midway between its sides and ends. The top member 1 adjacent each end has a downwardly extending 35 end board 8 of less length than the width of the top member 1, at each end of which there is at least one (there may be more than one) horizontally projecting pin 9.

40 A pair of extension slides is associated with and located at the under side of the top member 1. The middle slide member 10 of each of the pair of slides is permanently secured to, underneath and transversely of the top member 1 a short distance within the end boards 8. Outer extension slide members 11 and 12 of conventional structure are associated with the middle slide member 10 and are extensible to one side of the top member 1, while the inner extension slide members 11a and 12a are likewise associated together and with the middle slide members 10 for extension the other way from the top member 1.

The end slide members 12 and 12a are permanently secured to and lie above the bottoms 55 13 of end box structures each including vertical

ends 14 secured at each end of the bottom 13 and lying outside of the end slides 12 at one side of the table and further outside of the end slides 12a at the other end of the table. Each box structure is completed by a vertical rail 15 permanently connected with the bottom 13 and the ends 14 and may be secured to the outer ends of the slide members 12 and 12a. The hinges 4 by means of which the drop leaves are mounted are connected to the rails 15 at their upper edges.

A vertical pedestal 16 is secured at its upper end to each rail 15 substantially midway between the ends thereof extending downwardly parallel to the center pedestal 7. All of the pedestals 16 and 7 are provided with diverging legs 17 the lower ends of which rest upon the floor. The drop leaves are held in upper operative position by the usual folding brackets 18 commonly used with drop leaves for such purpose, one end being connected to a leaf and the other to the adjacent rail 15.

With this construction the table may be extended to either side of the permanent top member 1, or at both sides thereof. It is of course evident that when the extension slides are completely retracted the drop leaves 2 and 3 may be lifted and held in horizontal position, increasing the area of the top over that of the top member 1 by the combined areas of the two drop leaves 2 and 3. In Fig. 3 the extension slides at one side have been pulled out and the open space between the adjacent top member 1 and the drop leaf filled with fillers 19 which are of a special form. That is, one longitudinal edge of each filler 19 is recessed or grooved to correspond and be identical with the grooves shown at 5 in Fig. 1; the other edge of each filler leaf being shaped to make a rounded rib identical with the rib indicated at 6 for reception in a groove 5. As shown in Fig. 4 the grooved edge of a filler 19 will thus cooperate with the upper or inner edge of the drop leaf 3, adjacent grooved and ribbed edges of two fillers joined together, while a longitudinal rib on a filler 19 will fit a groove 5 on the top 1. The fillers at their grooved edges are provided with horizontally located holes 20, as are also the edges of the top member 1, the ribbed edges of the fillers having pins 21 to enter such holes. It may also be noted that the pins 9 on the end members 8 are adapted to enter holes for their reception made at the inner sides near the ends of the rails 15.

In Figs. 7 and 8 a further form or embodiment of the invention is shown. The top 1a is identical in general size and shape or form with the top 1 of the previous construction. In this form of the invention it is permanently secured to the end slides 12 as shown, of the extensible pair of slides. The rail 15 is permanently secured to the underside of the top adjacent an edge, the bottom member 13 and the ends 14 of the box being eliminated. The end boards 8 have the pins 9 at one end only, the other ends of said boards 8 coming to corner posts 22, one at each end of the rail 15. The drop leaf 2a hinged directly to the rail 15 is not separable from the adjacent edge of the top member 1a as before described but when lifted to horizontal position, as in Figs. 7 and 8, increases the area of the table 70 by the amount of its area. A horizontal board 23 lies between and is connected at the underside of the two middle slide members 10 of the extensible slides. The outer slide members 12a in this construction are permanently connected 75

to a box structure 13, 14a and 15 similar to that previously described, except the end members 14a of the box structure are of greater length than the members 14. At the outer end of end members 14a and at each end of the rail 15 a permanent downwardly extending corner post is secured. The table is thus supported by four corner posts. At the underside of the board 23 a foldable supporting drop leg 24 is mounted which may have a construction similar to that shown in United States Patent No. 2,268,042, granted December 30, 1941, or in the pending application of McFall and Langius, filed November 3, 1941, Ser. No. 417,612, which may be turned to vertical position to support the table on full extension. With this construction the part of the table carrying the drop leaf 3 may be moved away from the adjacent edge of the top 1a a distance equal to or less than the full extension permitted by the slides, the resulting space being filled with filler leaves 19 as indicated in Fig. 8.

This construction of table is particularly useful and practical and is of an efficient commercial form fully tested and in practical manufacture and sale.

The invention is defined in the appended claims and is to be considered comprehensive of all forms of structure coming within their scope.

I claim:

1. In a table, a solid horizontal top adapted to be positioned at a predetermined distance above a floor, said top having a straight side edge, said edge having a groove lengthwise thereof at its lower corner portion, extension slides connected at one end thereof to and under the top adapted to be extended outwardly beyond said side edge, a horizontal cross rail connected to the opposite end of the slides and movable outwardly and inwardly with respect to said edge of the top, said cross rail having its upper edge substantially in the same horizontal plane as the under side of the top, rigid vertically depending supporting means fixedly secured to said cross rail to maintain the cross rail at its upper edge substantially flush with the under side of the top at all extended positions and at the closed position of the slides, a drop leaf, and hinges connected to the cross rail at its upper edge and to the drop leaf at its inner side and spaced from the upper horizontal edge of the leaf a distance substantially equal to the greatest vertical dimension of said groove, the upper edge portion of the drop leaf above the hinge having a rib shaped for fitting into said grooved edge of the top, said grooved edge of the top having a recess therein covered by said rib when the slides are fully retracted, and uncovered when the slides are extended, whereby a filler leaf having a projection at the side edge thereof to enter said recess may be detachably connected with said top and held against longitudinal movement.

2. In a table, a horizontal top, depending leg-supporting means secured to the top adjacent one side edge of said top, the longitudinal side edge of said top opposite said leg supporting means having a groove undercut from said edge inwardly and downwardly to the lower side of the top, extendable slides each having one end portion connected to the under face of the top and extendable outwardly beyond said grooved edge of the top, a horizontal transverse bar connected to said slides at their outer ends, depending supporting means fixed to said bar to maintain it in the same plane in retracted and all extended positions of the slides, a drop leaf hinge means

connecting said bar and drop leaf to permit movement of said leaf from a vertical depending position to a horizontal position and vice versa, said hinge means being connected to the drop leaf at its inner side and spaced from its upper horizontal edge a distance substantially equal to the greatest vertical dimension of said groove, the upper edge portion of the drop leaf having a rib which, when the leaf is in depending position, extends above the upper edge of the bar and 10 covers said groove in the edge of the top when said slides are retracted, said rib having a form and shape complementary to said groove for entering and filling the groove when the drop leaf is moved to horizontal position when the slides are retracted, said grooved edge of the top having a plurality of horizontal pin receiving holes therein which are covered by the rib of the drop leaf when the slides are fully retracted and said leaf is in vertical depending position.
